UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed December 17, 1919. Serial No. 345,587.

To all whom it may concern:

Be it known that I, LIONEL M. WOOLSON, a citizen of the United States, and resident of Detroit, Wayne County, State of Michigan, have invented certain new and useful Improvements in Hydrocarbon Motors, of which the following is a specification.

This invention relates to hydrocarbon motors and more particularly to mechanism 10 for distributing gaseous fuel to the cylinders of hydrocarbon motors.

In a hydrocarbon motor such as is employed on motor vehicles and comprising four or more cylinders, one of the difficult 15 problems which confronts the designer is to secure a uniform distribution of fuel to all of the cylinders of the motor. Another problem is to break up the fuel in such a manner as to insure its ready and efficient 20 ignition.

The invention has for its objects, therefore, to overcome the above noted difficulties and to secure a uniform distribution of fuel to all of the cylinders of a hydrocarbon motor 25 and also to break up the fuel so as to insure its ready ignition.

The mechanism by means of which the above objects are carried out comprises briefly a member interposed between the intake manifold of a motor and the cylinders of the motor, this member in the embodiment 30 of the invention illustrated consisting of a screen by means of which the gaseous fuel is broken up and is uniformly distributed to the conduits which conduct the fuel to the cylinders.

One embodiment of the invention has been illustrated in the accompanying drawings, in which:

40 Figure 1 is a cross sectional view through the motor and intake manifold illustrating the screen in position between the manifold and the motor casing;

45 Figure 2 is an elevational view, partly broken away, at right angles to Figure 1;

Figure 3 is a transverse section of the construction shown in Figures 1 and 2 taken substantially at the longitudinal center thereof;

50 Figure 4 is a section of the construction shown in Figure 2 taken substantially on the line 4-4 of Figure 2; and

55 Figure 5 is a sectional detail view illustrating, on an enlarged scale, the screen construction.

The motor in connection with which my improved fuel distributing means is illustrated has four cylinders, these cylinders being arranged in pairs.

As illustrated in Figure 1, the cylinder block of the motor is provided with an elongated passage or chamber 10 into which the gaseous fuel passes from the intake manifold and from which the fuel is conducted through conduits 11 to the two pairs of cylinders. The elongated passage 10 in the cylinder block is open on one side and the intake manifold 12 is securely bolted to the block over the passage 10 and my improved distributing device is bolted between the manifold and the motor casing.

In the present invention this device has been combined with the gasket 13, the gasket comprising a pair of substantially parallel flat plates 14, these plates being connected 75 together in any suitable manner, or, if desired, being formed integral with each other. Suitable packing material 15, preferably formed of asbestos, is interposed between the two plates 14, two layers of this material 80 being illustrated in Figures 4 and 5. A screen 16 is positioned between the two layers of packing 15 and extends throughout the entire space between the members 14. As illustrated particularly in Figure 5, one 85 of the plates overlaps the other and is crimped or clamped on to this member, thereby retaining the plates 14 together and also clamping the screen between these members.

The gasket 13 is provided with a plurality of apertures adjacent its outer edge portion for the passage of bolts 17 for retaining the gasket and the manifold in position on the casing of the motor. In addition to this securing means for the screen and for the members 14 above described, several rivets 18 are provided adjacent the ends of the gasket, these rivets being headed over and providing for the passage of water conduits 100 to the water jacket 19 which surrounds the intake manifold.

My improved fuel distributing means operates as follows:

When the fuel enters the intake manifold 105 from the carburetor, the screen although not retarding the passage of the fuel to a sufficient extent to interfere with the operation of the motor does slightly retard the fuel passage to an extent sufficient to insure the uni- 110

form distribution of the fuel over the entire surface of the screen and, therefore, a uniform distribution to the conduits 11, which conduct the fuel to the motor cylinders. It 5 will be obvious that this result could not be obtained by interposing the screens in the conduits which conduct the fuel to the intake manifold since screens disposed in such a position would delay the passage of the fuel 10 to such an extent as to interfere with the efficient operation of the motor.

In addition to securing the uniform distribution of the fuel to the cylinders of the motor, the screen also breaks up the fuel 15 passing from the manifold to the motor in such a manner as to insure its ready ignition in the cylinders.

It should also be noted that my improved device utilizes the gasket as a retaining 20 means and in this manner avoids the use of additional parts and also securely retains the screen in position.

While I have in the above specification described one specific embodiment of my 25 invention, it should be understood that changes may be made without departing from the spirit or scope of the invention as expressed by the following claims.

What I claim and desire to secure by Letters Patent is:

1. In combination, a hydrocarbon motor comprising a plurality of cylinders, an elongated intake manifold secured to said motor and adapted to conduct the mixture 35 to said cylinders, and means extending throughout the length of said manifold and interposed between said intake manifold and the cylinders of said motor for securing a uniform distribution of fuel to said cylinders.

2. In combination, a hydrocarbon motor comprising a plurality of cylinders, an elongated intake manifold secured to said motor, and means extending throughout the 45 length of the manifold and interposed between said intake manifold and the cylinders of said motor for breaking up the fuel entering said cylinders from the manifold.

3. In combination, a hydrocarbon motor 50 comprising a plurality of cylinders, an intake manifold secured to said motor, and single means interposed between said intake manifold and the cylinders of said motor

and extending throughout the length of the manifold for breaking up the fuel entering said cylinders from the manifold and for securing a uniform distribution of the fuel to said cylinders.

4. In combination, a hydrocarbon motor comprising a plurality of cylinders, an intake manifold, a gasket between said intake manifold and the casing of said motor, and means carried by said gasket for securing a uniform distribution of fuel to said cylinders.

5. In combination, a hydrocarbon motor comprising a cylinder block having a plurality of cylinders, an intake manifold, a gasket between said manifold and the cylinder block of said motor, and a screen carried 70 by said gasket for securing a uniform distribution of fuel to said cylinders and for breaking up the fuel entering said cylinders from said manifold.

6. In a hydrocarbon motor, the combination with a cylinder block having an elongated passage for the inlet gases, said passage being open along one side thereof, of an elongated intake manifold adapted to be secured to the cylinder block over the open part of said passage, and means interposed between said manifold and the cylinder block for securing a uniform distribution of fuel to the cylinders.

7. In a hydrocarbon motor, the combination with a cylinder block having an elongated passage for the inlet gases, said passage being open along one side thereof, of an elongated intake manifold adapted to be secured to the cylinder block over the open part of said passage, and a screen interposed between the manifold and cylinder block for the purpose set forth.

8. In a hydrocarbon motor, the combination with a cylinder block having an elongated passage for the inlet gases, said passage being open along one side thereof, of an elongated intake manifold adapted to be secured to the cylinder block over the open part of said passage, and a gasket between the manifold and cylinder block and having an opening for the passage of the fuel, said gasket having a screen secured thereto covering the opening therein.

In testimony whereof I affix my signature.
LIONEL M. WOOLSON.
